UNITED STATES PATENT OFFICE.

ENOS C. VERKLER, OF CHICAGO, ILLINOIS.

GARMENT-HANGER.

1,204,618.

Specification of Letters Patent. Patented Nov. 14, 1916.

Application filed May 29, 1914. Serial No. 841,688.

To all whom it may concern:

Be it known that I, ENOS C. VERKLER, a citizen of the United States, and a resident of the city of Chicago, county of Cook, and 5 State of Illinois, have invented certain new and useful Improvements in Garment-Hangers, of which the following is a specification.

My invention relates to garment hangers 10 and has for its object the production of a garment hanger especially designed for use in connection with décolleté gowns or those which are low cut at the neck.

A further object is the production of a 15 hanger as mentioned which will be of simple construction and efficient in use.

Other objects will appear hereinafter.

With these objects in view my invention 20 consists in the combinations and arrangements of parts hereinafter described and claimed.

The invention will be best understood by 25 reference to the accompanying drawing forming a part of this specification, and in which,

Figure 1 is a perspective view of a garment hanger embodying my invention, Fig. 2 is a vertical longitudinal section of one 30 end of the hanger, and Fig. 3 is an enlarged section taken on line $x-x$ of Fig. 2.

The preferred form of construction as 35 illustrated in the drawing comprises an elongated curved or bowed body 1, formed preferably of wood. Projecting upwardly from the body 1 midway the ends thereof is a supporting hook 2, the lower end 3 of 40 said supporting hook being clenched at the under side of the body 1 so as to securely lock said hook in position as will be readily understood. The lower end of said hook 45 also pierces the under side of the body 1, as clearly shown in Fig. 2 in order to prevent relative rotation of the hook.

Arranged at the under side of the body 50 45 1 adjacent the extremities thereof are garment supporting hooks 4, the upper or outer ends of said hooks being driven into the body 1 and staples 5 being employed to securely fasten said hooks in position. The 55 hooks 4 are especially adapted for use in the support of a skirt, the skirt being suspended therefrom by engagement of the loops usually provided at the inner side of the waist band of the skirt with said hooks.

55 Arranged at the upper side of the body

1 are clamping arms 6 formed of spring wire, the inner ends of said arms being driven into the upper side of body 1 at either side of the supporting hook 2. The outer ends of said arms extend along the 60 upper side of the body 1, the outer enlarged extremities of said arms being adapted normally, by reason of the resiliency of said arms, to engage against the upper sides of the ends of the body 1 as 65 clearly shown in Figs. 1 and 2. The arms 6 are sprung upwardly to releasing position by means of finger pieces or buttons 7 which are slidably mounted in vertically extending openings 8 formed in the body 1, the members 7 being threaded to the lower ends 70 of studs 9 which are pivotally connected at their upper ends with ears 10 secured to the arms 6 intermediate the ends of the latter. With this arrangement it will be 75 seen that upward flexing of the arms 6 is readily and easily effected by pressing of the finger pieces 7 upwardly.

In the case of evening or décolleté gowns, where as is known, shoulder straps are very 80 narrow or spaced widely apart, the outer ends of clamping arms 6 will serve as a means of securely holding the shoulder straps of the gown in position upon the hanger, said shoulder portions being inserted under the outer ends of said arms 85 as will be readily understood. With this arrangement a gown of this character will be securely locked to the hanger so as to prevent accidental disengagement of the 90 gown from the hanger such as very frequently occurs where a hanger of the conventional construction is employed.

While I have illustrated and described the preferred form of construction for carrying 95 my invention into effect, this is capable of variation and modification without departing from the spirit of the invention. I, therefore, do not wish to be limited to the precise details of construction set forth, but 100 desire to avail myself of such variations and modifications as come within the scope of the appended claim.

Having described my invention what I 105 claim as new and desire to secure by Letters Patent is:

A garment hanger comprising an elongated body; spring clamping arms arranged at the upper side of said body having their inner ends secured to said body and their 110

outer ends normally engaging against the upper surface of said body, said body having vertically extending openings registering with said arms intermediate the ends thereof; stems pivotally connected with said arms and depending therefrom into said openings; and end pieces provided upon the lower ends of said stems and normally projecting below the under surface of said body

for manual engagement, substantially as described.

In testimony whereof I have signed my name to this specification in the presence of two subscribing witnesses.

ENOS C. VERKLER.
